UNITED STATES PATENT OFFICE

2,509,965

GARMENT CLASP

Irma M. Cowan, Chicago, Ill.

Application May 28, 1945, Serial No. 596,202

1 Claim. (Cl. 24—248)

1

My invention is concerned with improvements in a clasp or fastener particularly adapted for use on wearing apparel or other articles of cloth or fabric.

A principal object is to provide a very thin fastener which securely grips the fabric and does not puncture or tear the same.

A further object is to provide a simple, light weight, easily made fastener of thin hard durable metal which is ruggedly constructed of relatively few parts and which can be manufactured cheaply and in large quantities.

A more specific object is to provide a fastener having a member adapted to be readily secured to a garment or the like, and, cooperating, pivotally mounted members, adapted to engage and securely grip a portion of another garment.

Other objects will be apparent from the following specification which describes a specific embodiment of the device, by way of example, as illustrated in the accompanying drawings.

In the drawings:

Fig. 1 is a plan view of the fastener engaged on a garment edge;

Fig. 2 is a plan view showing the opposite side of the fastener;

Fig. 3 is a side view of the fastener as shown in Fig. 1;

Fig. 4 is a view showing the fastener in open position with the garment edge in position for engagement;

Fig. 5 is a view similar to Fig. 3, showing the fastener in partially closed position;

Fig. 6 is a view showing part of the fastener in the position shown in Fig. 1, but to a larger scale;

Fig. 7 is a view similar to Fig. 6, showing the fastener in open position;

Fig. 8 is a view illustrating a blank cut out to form one of the fastener members;

Fig. 9 is a view, with the clamping members broken away, illustrating a modified form of a fastener member;

Fig. 10 is a view similar to Fig. 1, showing the clasp used with a garment hook fastener member; and

Fig. 11 is a perspective view of the garment hook fastener member per se.

My fastener comprises three members, stamped and formed from thin sheet metal, a securing or fastening member 10 and cooperating gripping members 11 and 12. The securing or fastening member 10, which is adapted to be secured to a garment, is generally U-shaped in form, having a base 13 and legs 14. On or adjacent the ends of

2

the legs 14 are located outwardly extending pins or trunnions 15. Intermediate the ends of the legs 14 there are provided inwardly directed pins or trunnions 16. One gripping member 11 is provided with journals 17 which receive the pins 16 to hingedly connect the members. The other gripping member 12 is provided with journals 18 which receive the pins 15 to hingedly connect the members. Gripping member 11 comprises a garment engaging portion having an aperture 19 adapted to receive the free end of gripping member 12 and a portion 20 which carries the journals 17. The gripping member 12 comprises a garment engaging tongue or free end portion 21 and laterally spaced parallel legs 22 on the ends of which are located the journals 18. The free end 21 of member 12 is adapted to be received within the aperture 19 of the member 11 when the gripping members are in fastening engagement with the garment. The lip or tongue portion 21 (Fig. 5) is provided on the end of member 12 for greater surface engagement with the face of the end portion 24 of member 11.

The member 11 is pivoted to member 10. Member 12 has a pivotal connection with member 10, which includes specially constructed journals for receiving the pins 15. The construction of the journals is more clearly illustrated in Figs. 6 to 8. Referring to Fig. 8, there is depicted a blank from which member 12 is formed. Each leg 22 has a portion 26, 27 cut away at the end terminating in a cam surface 28 on one leg and abutment stop 29 on the other leg. When the journals are formed by curling back the ends of the legs over the pins 16 of member 10, the members are so proportioned that there is sufficient frictional engagement between the surfaces 26, 27 and the adjacent edges of the legs 14 of the member 10 to, first, lightly resist relative movement of the members 10 and 12 about the pivot pins, then, to provide increased friction between the members, as they are moved toward each other, about their pivots, by engagement of the left leg 14, as seen in Fig. 6, with the cam surface 28, and finally, a positive stop as the right leg 14 engages the stop surface 29 as seen in Fig. 7. The purpose of this construction is to control the movement of gripping member 12 by movement of the member 10. In the specific construction illustrated the engagement of the leg 14 with the cam surface 28 forces or spreads the legs 22 apart and due to the resiliency of the material the friction between the members is such that the member 12 will be held in the position 55 with respect to member 10 to which it has been

removed. The engagement of leg 14 with the stop surface 29, of course, stops the movement of member 12 in a predetermined position with respect to member 10.

The operation of the device will be understood from Figs. 3, 4 and 5. In Fig. 4 the gripping members 11 and 12 are shown in open position approximately at right angles to the member 10 and separated to receive between them the garment edge or portion to which the fastener is to be applied. As seen in Fig. 5, movement of the member 10, which functions as a manipulator member, about the pivot 16 carries the member 12 toward the member 11, projecting a portion of the garment through the aperture 15. Further movement of manipulator member 10 about the pivot 16 causes the gripping member 12 to move inwardly and then upwardly into the position shown in Fig. 3 where the garment is securely locked between the surface 21, 23 of the gripping members 12 and 11, respectively.

My fastener is particularly adapted for use in securing one garment in relation to another, such as a lady's skirt and shirtwaist. Fastening member 10 may be attached to either garment in any suitable manner while the gripping members are moved into closed position to engage an edge or fold of the other garment.

My fastener may be used also as a hose support or belt fastener. Fig. 9 shows a modified form a fastener member 10a having an eye 30 through which a hose supporter or belt web may be threaded and secured.

In Fig. 10 there is illustrated an alternative use of the clasp fastener device wherein a separable hook fastener member 40 is provided which is intended to be attached to a garment by sewing 41 or similar attaching means. The garment to which it is attached may be, for example, a shirtwaist; the clasp 10 would then be secured to a skirt. The fastener 40 is provided with a hook 42 which is adapted to be inserted in the aperture 19 of the clasp member. By this arrangement only the small fastener member 40 is attached to the clothing while the clasp member 10 is unattached and may be removed from the garment and used separately. The clasp is more readily manipulated when the member 40 is not attached to the garment. The hook fastener per se is more clearly illustrated in Fig. 11, but it is obvious that it need not take the specific form there illustrated.

It will be understood that the fastener may be made of materials other than thin sheet metal. The relative size and shape of the clamping members may be changed, as well as the thickness in cross section without altering the operation of the fastener or the principle of the invention. While the fastener as illustrated is preferably made by stamping from thin metal, it may be made by other well known manufacturing methods.

I claim:

A fastener device comprising a member having spaced parallel legs, outwardly directed trunnions on said legs and inwardly directed trunnions on said legs in parallel spaced relation to said outwardly directed trunnions, an apertured clamp member pivotally mounted on said inwardly directed trunnions, a clasp member having an offset tongue adapted to be engaged in the aperture in said apertured clamp member and laterally spaced journals pivotally received on said outwardly directed trunnions, the inward edge of one of said journals having a cam surface and the inward edge of the other of said journals having a stop member, whereby, upon movement of said clasp member and said clamp member about said trunnions to disengage the tongue of the former from engagement in the aperture of the latter, the said cam surface is first engaged by the adjacent edge of the one leg and the stop member is subsequently engaged by the adjacent edge of the other leg upon predetermined further movement of said clamp member to control the movement of the clasp member with respect to the clamp member and to stop the same in position for proper reengagement.
